US0D1025494S

(12) **United States Design Patent** (10) **Patent No.:** **US D1,025,494 S**
(45) **Date of Patent:** **** Apr. 30, 2024**

(54) **ISOLATION APPARATUS**

(71) Applicant: **AerosolShield Limited**, Birmingham (GB)

(72) Inventor: **Matthew James Campbell-Hill**, Birmingham (GB)

(73) Assignee: **AerosolShield Limited**, Birmingham (GB)

(**) Term: **15 Years**

(21) Appl. No.: **29/809,690**

(22) Filed: **Sep. 29, 2021**

(30) **Foreign Application Priority Data**

Mar. 31, 2021 (GB) 6127794
(51) **LOC (14) Cl.** **24-02**
(52) **U.S. Cl.**
USPC **D24/217**

(58) **Field of Classification Search**

USPC D29/101.1, 107, 124; D24/183, 184, D24/190, 202, 217

(57) **CLAIM**

The ornamental design for an isolation apparatus, as shown and described.

DESCRIPTION

FIG. 1 is a front left perspective view of an isolation apparatus showing my new design;
FIG. 2 is a front view of the design shown in FIG. 1;
FIG. 3 is a rear view of the design shown in FIG. 1;
FIG. 4 is a left side view of the design shown in FIG. 1;
FIG. 5 is a right side view of the design shown in FIG. 1;
FIG. 6 is a top view of the design shown in FIG. 1;
FIG. 7 is a bottom view of the design shown in FIG. 1;
FIG. 8 is a rear perspective view of the design shown in FIG. 1 in a first example use state;
FIG. 9 is a front perspective of the design shown in FIG. 1 in a second use state; and,
FIG. 10 is a top perspective view of the design shown in FIG. 1 in a third use state.
The broken line showing of the people and pillow depict environment and form no part of the claimed design.

1 Claim, 10 Drawing Sheets
